RECORD RACK

Eugene C. Clarke, Chambersburg, Pa., assignor to Chambersburg Engineering Company, Chambersburg, Pa., a corporation of Pennsylvania

Application January 22, 1957, Serial No. 44,538

Term of patent 3½ years

(Cl. D33—3)

FIG.1.

FIG.4.

FIG.2.

FIG.3.

Fig. 1 is a perspective view of a record rack embodying my design;

Fig. 2 is a top plan view;

Fig. 3 is a front elevational view; and

Fig. 4 is a transverse section taken on the line 4—4 of FIG. 3 thereof.

I claim:

The ornamental design for a record rack, as shown.
